RAIL JOINT

Philippe Pelletier and Philias Vaillancourt,
Beaupre, Quebec, Canada

Application February 3, 1936, Serial No. 62,019

2 Claims. (Cl. 238—218)

The present invention pertains to a novel joint for the ends of rails in a railway track.

One of the objects of the invention is to provide an effective joint of this character wherein the space occurring between the rail ends is properly filled by parts of the joint pieces, at the same time allowing for the expansion and contraction of the various parts in response to changes in temperature. Consequently, certain parts of the joint pieces must enter between the rail ends, and the invention further provides for proper bearing surfaces between these intervening members. Still another object of the invention is to provide means to facilitate the assembly of the parts before they are finally secured together.

In the accomplishment of these objects, there are provided similar joint pieces adapted to engage opposite sides of the rails to be joined. The ends of the rails are maintained a considerable distance apart, and the upper edges of the joint pieces are formed with triangular heads adapted to engage one another and form a rectangle filling this space and constituting a continuation of the tread of the rail. In order to furnish sufficient bearing surfaces for the parts inserted between the rail ends, the joint pieces are formed with oblique cheeks beneath the heads, the faces thereof of contacting one another.

Each rail end and the joint pieces at opposite sides thereof are apertured to receive tie bolts. To facilitate bringing these respective openings into alignment, each joint piece is formed with a peg adapted to enter another opening in the adjacent rail. After assembly in this manner, the bolt holes are in alignment, and the bolts are readily inserted and tightened. In each set of three aligned bolt holes, one hole is elongated lengthwise of the rail to permit expansion and contraction under temperature changes.

The invention is fully disclosed by way of example in the following description and in the accompanying drawing in which

Figure 1 is a perspective view of a joint made according to the invention;

Figure 2 is a perspective view showing one of the joint pieces and one rail end;

Figure 3 is a perspective view of one of the joint pieces;

Figure 4 is a sectional view of a rail showing the end pieces in elevation;

Figure 5 is a horizontal section of the parts illustrated in Figure 2, and

Figure 6 is a horizontal section of the complete joint in the plane of the tie bolts.

Reference to these views will now be made by use of like characters which are employed to designate corresponding parts throughout.

As shown particularly in Figures 1, 2, and 4, the joint is made by means of two like joint pieces 1 and 2 at opposite ends of the rails 3 and 4 that are to be connected. The ends of the rails are spaced slightly to accommodate certain parts as shown in Figures 1 and 6 and as will be described more fully below. The bottoms of the pieces 1 and 2 meet beneath the bases of the rails as indicated by the numeral 5 in Figure 4. The webs 6 of the joint pieces have their upper ends sloped at 7 to engage beneath the heads of the rails 3 and 4 as also shown in Figure 4.

In substantially the central part of each upper edge 7 is formed a flat triangular head 8 having its two outer edges forming a right angle and its oblique edge disposed inward. These members on the two joint pieces 1 and 2 are so arranged that their oblique edges engage one another in the assembly to form a rectangle filling the space between the ends of the rails as clearly illustrated in Figure 1. Beneath each head 8 is formed an oblique cheek 9, these members contacting one another in the assembly to provide adequate bearing or contact surface beneath the heads 8 as shown in Figure 6.

Each web 6 is formed with two oval openings 10 at one side of the cheek 9 and with two round holes 11 at the other side of the cheek. Between the holes 11 is a peg 12 for a purpose that will presently be described.

The groove 13 that receives the bases of the rails has a tooth 14 projecting inward from its lateral wall, as shown in Figure 5, and engaging a notch 15 formed in the adjacent rail base. This construction prevents the rail from slipping away from the joint piece, or vice versa, after the joint has been assembled.

The holes 10 and 11 of each joint piece come into alignment with the holes 11 and 10 respectively of the other joint piece when the pieces are assembled at opposite sides of the rail. Between these holes, the webs of rails are apertured at 16 so that bolts 17 may be passed through each set of three holes as illustrated in Figure 6. The joint pieces are clamped to the rails between the heads 18 at one end of each bolt and the nuts 19 at the other end. It will be seen that proper alignment of the holes in the rails and joint pieces is attained by means of the pegs 12 entering certain of the holes 16 in the rails.

The bases of the joint pieces are formed at the outer edges with notches 20 for receiving spikes

driven into the ties or sleepers to anchor this part of the rail.

Each of the bolts 17 is received in at least one oval opening 10 which allows expansion or contraction of any of the parts in response to temperature changes.

Although a specific embodiment of the invention has been illustrated and described, it will be understood that various alterations in the details 10 of construction may be made without departing from the scope of the invention, as indicated by the appended claims.

What we claim is:—

1. A rail joint comprising two like pieces 15 adapted to engage opposite sides of the rails to be joined, each piece having at its upper edge a horizontal triangular head adapted to enter the space between the rail ends, oblique cheeks formed on said pieces beneath said heads and engaging one

another on their oblique surfaces, said heads forming a rectangle filling said space and constituting a continuation of the heads of the rails, and means for securing said pieces to said rails.

2. A rail joint comprising two like pieces 5 adapted to engage opposite sides of the rails to be joined, each piece having a channel adapted to receive one side of the base from each rail, each piece having at its upper edge a horizontal triangular head adapted to enter the space between 10 the rail ends, oblique cheeks formed on said pieces beneath said heads and engaging one another on their oblique surfaces, said heads forming a rectangle filling said space and constituting a continuation of the heads of the rails, and means for 15 securing said pieces to said rails.
